VOTING MACHINE

Richard D. Uhthoff, Creskill, N. J., assignor of one-tenth to Benjamin Webster and nine-twentieths to Thomas A. Dobson, both of New York, N. Y.; Frieda M. Uhthoff administratrix of said Richard D. Uhthoff, deceased

Application December 18, 1929, Serial No. 414,927
Renewed November 29, 1933

5 Claims. (Cl. 235—51)

This invention relates to voting machines and more particularly to that type in which there are vertical columns of voting devices.

Among the objects of the invention are, first, to provide a simple and dependable mechanism whereby one or a predetermined plurality of votes may be registered in any vertical column and when said one or plurality of votes as predetermined shall have been registered on the machine to positively lock all the other voting devices in said vertical row against registering; and second, to provide a simple and dependable means for altering the locking mechanism to permit one or a plurality of votes on said vertical column as may be predetermined.

This invention is intended for application to a voting machine of the type illustrated and described in Patent No. 1,131,363 to J. C. Garrett, March 9, 1915. In my copending applications Serial Number 414,928 filed Dec. 18, 1929, and Serial Number 414,923, filed Dec. 18, 1929, I illustrate and describe improved mechanism for controlling the vote-registering buttons, comprising a vertical bar that moves in a vertical direction when any knob is turned to register a vote in the machine, all of said mechanisms being intended for use on the type of voting machine disclosed in the Garrett Patent No. 1,131,363 above cited. The control of the number of vertical motions of a vertical bar as disclosed in my copending applications for patent above cited is positively and easily effected by the mechanism hereinafter disclosed. It is believed to be perfectly obvious from the disclosure in my copending applications for patent above cited, that the operation of my improved mechanism may be defined either in the terms of the control of the motion of any vertical bar or of the mechanism of a voting machine in which this mechanism is especially intended to be used.

In the accompanying drawing which is a part of this specification

Figure 1 is a rear elevation embodying a preferred form of my invention,

Figure 2 is an elevation of the lower portion of my locking device,

Figure 3 is an elevation of the upper portion of my locking device, and

Figure 4 is an elevation partly in section on line 4 of Figure 2 through the center of the locking device as viewed from the left.

In the drawing like numerals of reference indicate like parts throughout the specification. Referring to Figure 1 the lower portion 1 of my locking device is in the form of a wedge of sheet

metal, having formed in the bottom a horizontal slot 2 by means of the marginal wall 3. The lower portion 1 of my locking device is supported by the slot 2, on a stud bolt 4 which passes through the slot 5 in the front wall 6 and is secured in a vertical bar 20 of the machine, and is held on said bolt by the split washer 7. It will be understood from my copending applications for patent above cited that the vertical bar 20 is one of the vertical bars of a voting machine of the type disclosed in the Garrett patent above cited that is actuated by a voting button. Cams on the voting button shaft intercept studs on the lower portion of the vertical bar 20 and move it upwards one predetermined space each time the voting button and its shaft is turned to record a vote. This mechanism therefore by definitely limiting the number of upward motions of a vertical bar 20 to any predetermined number obviously limits the number of votes that may be made on the voting buttons in any vertical column of voting buttons connected with the same vertical bar 20. The upper part 8 of the locking device is in the form of an acute angle and is provided with a central vertical slot 9 by means of which it may be adjusted up or down by means of the two screws 10, 10 adapted for attachment at 11, 11 to the lower portion 1. In order to set the locking device quickly and truly to lock a vertical bar after one or a plurality of vote-registering motions upward by said bar, I mark the upper part 8 of the locking device with lines which with arrow 21 on the part 1 indicates the appropriate setting position to permit of and limit the voting under control of said vertical bar to the predetermined and selected number, as shown in Figure 3. In order to positively and definitely restrict the vertical movement of a wedge 8 on either side there is mounted on the inner side of the front wall 6 of the machine a lug 12 by means of two screws 13, 13. The lug 12 is provided with a rearward extension 14 in the form of a round bearing hole 15 through which the horizontal rod 16 is supported, the bar 16 being a support which prevents the edges 8 of the wedge from moving back by bending or buckling to escape the inclined upper and lower edges 17 and 18 respectively of adjacent lugs 12. The angle of inclination of the edges 17 and 18 is similar to that of the edges of the wedge 8.

It is obvious that any number of locking devices may be used on as many vertical bars as desired. Having now particularly pointed out and described one of the preferred forms of my invention, I do not choose to limit myself except as in the appended claims.

I claim:

1. In a voting machine, a vertical bar for controlling the registering of a vote, a device for locking said bar against vertical movement mounted on said vertical bar, said locking device comprising a wedge-shaped upper portion and a wedge-shaped lower portion, means for adjustably securing one portion to the other, a horizontal slot in the lower portion and means secured 10 to a vertical bar and adapted to support said locking device in said horizontal slot.

2. In a voting machine, a vertical bar for controlling the registering of a vote, a device for locking said bar against vertical movement mounted 15 on said vertical bar, said locking device comprising a wedge-shaped upper portion and a wedge-shaped lower portion, a longitudinal slot in one portion and set screws for adjustably locking said portions together, and two stops mounted on the 20 machine one on either side of said wedge-shaped upper portion having its edge surface inclined in a plane substantially parallel to that of the proximate edge of said wedge-shaped portion.

3. In a voting machine, a vertical bar for controlling the registering of a vote, a device for locking said bar against vertical movement mounted on said vertical bar, said locking device comprising a wedge-shaped upper portion and a wedge-shaped lower portion, a longitudinal slot 25 in one portion and set screws for adjustably locking said portions together, and two stops mounted on said machine one on either side of said wedge-

shaped upper portion and means adapted to engage the front of said upper portion and to guide it.

4. In a voting machine, a vertical bar for controlling the registering of a vote, a device for locking said bar against vertical movement mounted on said vertical bar, said locking device comprising a wedge-shaped upper portion and a wedge-shaped lower portion, a longitudinal slot in one portion and set screws for adjustably locking said portions together, and two stops secured to said machine 80 adapted to engage said wedge-shaped portion, each stop being provided with a transverse aperture and a rod adapted to be passed thru said apertures and to overlie the front of said wedge-shaped portion.

5. In a voting machine, a vertical bar for controlling the registering of a vote, a device for locking said bar against vertical movement mounted on said vertical bar, said locking device 95 comprising a wedge-shaped upper portion and a wedge-shaped lower portion, means for adjustably securing one portion to the other, a horizontal slot in the lower portion and means secured to a vertical bar and adapted to support said locking 100 device in said horizontal slot, and two stops mounted on the machine one on either side of said wedge-shaped upper portion having its edge surface inclined in a plane substantially parallel to that of the proximate edge of said wedge-shaped portion.
